UNITED STATES PATENT OFFICE.

HARRY S. HART, OF CHICAGO, ILLINOIS.

DUMP-CAR CONSTRUCTION.

1,300,960.

Specification of Letters Patent. Patented Apr. 15, 1919.

Application filed November 4, 1918. Serial No. 280,925.

To all whom it may concern:

Be it known that I, HARRY S. HART, a citizen of the United States, residing at Chicago, in the county of Cook and State 5 of Illinois, have invented certain new and useful Improvements in Dump-Car Constructions, of which the following is a specification.

This invention relates to dump cars.

10 The object of this invention is to simplify and improve dump car constructions in a novel manner to increase the capacity thereof and at the same time retain the self cleaning feature.

15 This and other objects are accomplished by means of the arrangement disclosed by the accompanying sheets of drawings in which—

20 Figure 1 is a fragmentary side elevation of a railway dump car embodying my invention;

Fig. 2 is a fragmentary plan view of the same car;

25 Fig. 3 is a transverse sectional view of the same dump car taken over one of the trucks; and

Fig. 4 is a transverse sectional view of the same car taken between the trucks.

30 It is a well recognized fact that it is of vital importance to increase the carrying capacity of railway cars and especially dump cars for carrying coal and other dumpable materials in view of the great demand as a result of traffic conditions.

35 In one well known type of dump car in which the floor intermediate the trucks is flat and composed of a plurality of transversely hinged doors and in which the floor portions over the trucks include a long sloping member 40 extending from the end of the car downwardly toward the transverse center line of the car, it is found that the capacity can be effectively increased by changing the floor construction over the trucks.

45 Referring to the figures of the drawings, it will be noted that I have shown a dump car including sides 10, ends 11 and a floor, the floor portions over the trucks being of A-shaped construction in which the apex 12 50 of the A is located over the center sill 13, the sloping members 14 of the A-shaped portion extending downwardly and outwardly toward the sides of the car. These sloping floor members 14 preferably are stationary and connected to the under frame to thereby increase the stiffness and rigidity of

the car structure. The discharge openings at the lower ends of the floor portions 14 normally are closed by side dump doors 15 which preferably are pivotally connected at 60 16 along the lower edges of the sides 10 of the car, the swinging edges of the doors 15 when in closed position forming a tight seal with the lower edges of the floor members 14. The dump doors 15 may be provided with any suitable operating mechanism including operating shafts 17, preferably carried by the doors 15, and also chains 18, which connect the shafts with the stationary floor portions 14.

70 The floor intermediate the trucks is flat and at a lower level than the floor portions over the trucks and includes a plurality of transversely hinged dump doors 19, the doors preferably being arranged in pairs 75 and swinging toward and from each other to closed and opened positions respectively. Leading from the extreme doors 19 nearest the ends of the car are sloping floor members 20 which extend to the apex 12 of the floor 80 portions over the trucks. In cars heretofore built the sloping floor portions 20 at each end is continued in the same plane to the end of the car. It is apparent, therefore, that by providing the floor construction over the 85 trucks as disclosed in this application the carrying capacity of the dump car is greatly increased and at the same time the self cleaning feature is retained. When the side dump doors 15 are opened it will be appreciated that all of the dumpable material over the trucks will be discharged to either side of the car, and when the transversely arranged dump doors 19 are opened the remaining dumpable material in the car will 90 be discharged intermediate the trucks, whereby the car will be substantially self cleaning. The transversely hinged dump doors 19 may be provided with any suitable operating mechanism 21.

100 It is my intention to cover all of the modifications falling within the spirit and scope of the following claims.

I claim:—

1. In a car of the class described having 105 sides, ends, and a floor, the floor over the trucks comprising portions sloping downwardly and outwardly toward the sides of the car, the floor intermediate the trucks being flat and at a lower level than the floor 110 portions over trucks and including a plurality of transversely hinged doors.

2. In a car of the class described having sides, ends, and a floor, the floor over the trucks comprising stationary portions sloping downwardly and outwardly toward the sides of the car, the floor between the trucks being flat and comprising a plurality of doors hinged transversely of the car and swinging toward and from each other to closed and opened positions respectively.
- 10 3. A car of the class described having sides, ends, and a floor, the floor over the trucks comprising stationary portions sloping downwardly and outwardly toward the sides of the car, side dump doors associated with said sloping portions for dumping a part of the load to the sides of the car, the floor between the trucks being flat at a lower level than the portion over the trucks and

comprising a plurality of transversely hinged doors, and door operating mechanism for said doors. 20

4. A car of the class described having a single floor which at the ends of the car comprises stationary portions sloping downwardly and outwardly toward the side of the car, doors hinged to the side of the car and coöperating at their swinging edges with the outer edges of the sloping floor portion, the remainder of the floor being substantially horizontal and composed largely of doors arranged to drop to discharge the load, and operating mechanism for said doors. 25

Signed at Chicago, Illinois, this 30th day of October, 1918.

HARRY S. HART.
